UNITED STATES PATENT OFFICE.

WILLIAM HENRY MORGAN, OF ALLIANCE, OHIO.

FLANGING-PRESS.

1,288,648.

Specification of Letters Patent. Patented Dec. 24, 1918.

Original application filed May 5, 1917, Serial No. 166,735. Divided and this application filed December 1, 1917. Serial No. 204,883.

To all whom it may concern:

Be it known that I, WILLIAM H. MORGAN, a citizen of the United States, and a resident of Alliance, in the county of Stark and State of Ohio, have invented certain new and useful Improvements in Flanging-Presses; and I do hereby declare the following to be a full, clear, and exact description of the invention, such as will enable others skilled in the art to which it appertains to make and use the same.

My invention relates to improvements in forging, flanging and other presses and is a division of application Serial Number 15 166735, filed by me May 5, 1917.

Heretofore presses of this type, designed for heavy work, have been operated by hydraulic mechanism which is necessarily complicated in construction and requires constant attention, frequent repairs and adjustment of parts in order to maintain them in proper working condition.

The object of my invention is to simplify and consequently cheapen the cost of construction and the expense of upkeep, by dispensing with the hydraulic devices and actuating the movable platen by nuts driven by an electric motor, and it consists in the parts and combination of parts and in the 30 details of construction as will be more fully explained and pointed out in the claims.

In the accompanying drawings, Figure 1 is a view partly in section and partly in elevation of a press embodying my invention. 35 Fig. 2 is an end view of the same. Fig. 3 is a sectional plan view showing the worm shaft. Fig. 4 is a view partly in section and partly in elevation of a modification. Fig. 5 is an end view of the latter, and Figs. 6 and 40 7 are similar views of another modification.

While I have illustrated my improvement as applied to forging presses it is equally applicable to flanging, bending and other presses, hence I would have it understood 45 that it is not confined in its application to any particular kind of press, but is equally applicable to all apparatus of the types above referred to.

5 represents the lower platen carrying an 50 anvil or die 6, and 10 is a movable platen

mounted to move on the four columns 7. These columns are secured at their lower ends to the lower platen 5, and they are threaded at their upper ends as shown, the said threads being engaged by the internal threads of the internally and externally threaded nuts 8, the external threads of the latter meshing with the internal threads of the fixed nut 9. This nut 9 is secured within the upper platen 10, the four nuts 9 being located adjacent the four corners of the platen, or equidistant apart in the event the platens are circular instead of square or rectangular. Mounted within the upper platen 10, are the worm wheels 11, one for each of the movable nuts 8, each wheel being connected by spline and groove connection with its respective nut 8. The worm wheels 11 are housed within the top platen and are held by said housing against movement other than their normal rotary movement, hence when they are rotated the nuts 8 move vertically up or down within the hubs of the worm wheels, their movement being permitted by the spline and groove connection between the 75 wheels and nuts.

Mounted on top of platen 10, is the electric motor 12, the armature shaft of which carries a pinion 13 meshing with a pinion 14 on the worm shaft 15. This shaft extends 80 lengthwise the upper platen, between the four worm wheels housed in the latter, and meshes with said wheels so that all turn in unison and in a direction to raise or lower the platen 10. The nuts 9 and 8 and the columns 7, are so threaded that when the worm wheels 11 are rotated by the worm shaft 15, the movable nuts 8 will all move in the proper direction and at the same rate of speed so as to raise or lower the movable 85 platen, and the threads are so formed that when the movable nuts 8 are rotated, they move vertically up or down on the threaded columns, and up or down in the fixed nuts 9, so that the movable platen 10 has a vertical 90 movement equal to the combined movements of the movable nuts in the fixed nuts, and the vertical movement of the movable nuts on the screws.

It will therefore be seen that by rotating 100

the worm shaft 15, the movable nuts 8 will be rotated and moved longitudinally in the fixed nuts, and on the screws, thus moving the upper die 16, carried by the upper platen 10 toward or away from the lower die, the speed of such movement being controlled by the motor controlling devices.

In the construction shown in Figs. 4 and 5 the columns 7^b are secured to the upper movable platen 10^a and threaded at their lower ends to engage the internal threads on the internally and externally threaded nuts 8, the external threads of which engage internal threads on the fixed nuts 9 secured to the four corners of the lower fixed platen 5^a, the worm wheels 11, which in this construction are housed in the lower fixed platen, having spline and groove connection with the movable nuts 8 so as to permit the latter to move up and down as in the construction previously described.

The worm shaft 15 which actuates the worm wheels 11, is in this instance down adjacent the floor line, and may if desired be connected with a motor removed from the press. This construction is substantially like that shown in Figs. 1 and 2 inverted and the motor removed.

In the construction shown in Figs. 6 and 7 I have dispensed with the internally and externally threaded nuts of the previously described apparatus so that the internally threaded nuts 9^a which are mounted to turn in the upper platen 10, directly engage the threads on the columns 7^a and are integral with or rigidly connected with the worm wheels 11^a so that they are rotated by the latter.

It is evident that changes might be resorted to in the relative arrangement of parts shown and described without departing from the spirit and scope of my invention as claimed, hence I would have it understood that I do not confine myself to the exact details as shown, but consider myself at liberty to make such changes as may fairly fall within the spirit and scope of the claims.

Having fully described my invention what I claim as new and desire to secure by Letters-Patent, is:

1. In a press for forging, flanging, etc., the combination of two platens one being fixed and the other movable, and each carrying a metal working member, a plurality of threaded columns secured to one of said platens, a nut for each threaded column, the said nuts being carried by said other platen and an electric motor and gearing carried by the latter platen for rotating the nuts simultaneously whereby the movable platen will be removed toward or away from the other platen.

2. In a press for forging, flanging, etc., the combination of two platens one being fixed and the other movable, and each carrying a metal working member, a plurality of threaded columns rigidly secured to one of said platens and passing through the other platen and engaging the threads on the several columns, gearing connected with the nuts and a motor for actuating said gearing whereby the nuts will be rotated simultaneously.

3. In a press for forging, flanging, etc., the combination of two platens one being fixed and the other movable, a plurality of threaded columns rigidly secured to one of said platens and passing through the other, internally threaded nuts rigidly secured to the latter platen, an internally and externally threaded nut within and engaging the threads of each fixed nut and also engaging the threads on the columns, a gear wheel having sliding engagement with each internal and external threaded nut and means for rotating the series of gear wheels.

4. In a press for forging, flanging, etc., the combination of two platens one being fixed and the other movable, a plurality of threaded columns rigidly secured to one of said platens and passing through the other, internally threaded nuts rigidly secured to the latter platen, an internally and externally threaded nut within and engaging the threads of each fixed nut, and also engaging the threads on the columns, a worm wheel having sliding engagement with each internal and external threaded nut and a single worm shaft for actuating the series of worm wheels.

5. In a press for forging, flanging, etc., the combination of a fixed platen, a plurality of columns rigidly secured at their lower ends to said fixed platen and threaded at their upper ends, a movable platen carrying a series of internally threaded nuts, one for each threaded column, a gear wheel having connection with each nut for rotating the same, gearing engaging the several worm wheels for rotating the latter in unison and an electric motor carried by said movable platen and having gearing for rotating the worm shaft.

6. In a press for forging, flanging, etc., the combination of a fixed platen, a plurality of columns rigidly secured thereto and projecting upwardly, the upper portions of said columns being threaded, an upper movable platen, a fixed nut for each threaded column, the said nuts being internally threaded, a movable nut for each fixed nut, each movable nut having external threads for engagement with the internal threads on the fixed nuts, and internal

threads for engagement with the external threads on the columns, a worm wheel for each movable nut, the latter having sliding engagement with its worm wheel, a worm shaft for actuating the several worm wheels, and a motor and gearing carried by the movable platen for rotating the worm shaft.

In testimony whereof, I have signed this specification in the presence of two subscribing witnesses.

WILLIAM HENRY MORGAN.
